UNITED STATES PATENT OFFICE.

AUGUST ARENS, OF NEW BRITAIN, CONNECTICUT, ASSIGNOR TO AMERICAN HARDWARE CORPORATION, OF NEW BRITAIN, CONNECTICUT, A CORPORATION OF CONNECTICUT.

LOCK.

1,043,750.

Specification of Letters Patent.

Patented Nov. 5, 1912.

Application filed June 1, 1912. Serial No. 700,915.

To all whom it may concern:

Be it known that I, AUGUST ARENS, a citizen of the United States, residing at New Britain, county of Hartford, State of Connecticut, have invented certain new and useful Improvements in Locks, of which the following is a full, clear, and exact description.

My invention relates to an improvement 10 in locks, particularly of the type disclosed in United States Letters Patent No. 834,994, the present invention including, of course, changes in structure whereby improved results are attained and whereby the lock is 15 made of particular service in connection with corridor doors for hotel apartments and the like.

So far as the present construction embodies features in common with the afore- 20 said patent, it is unnecessary to describe the same at length, but only in so far as necessary to give a general idea.

Among the main objects of the present invention are to provide means whereby the 25 occupant of an apartment in a hotel or other building may securely lock the corridor door from the inside by turning a small knob or so-called "thumb-turn", and may instantly 30 unlock the door by simply turning the inside knob, which act of itself not only withdraws the latch in the usual manner, but also casts off the dogging device operated by the thumb-turn. Thus, when it is desired to 35 make a hasty exit, as in case of fire, the occupant may instantly leave the room without the embarrassment of casting off the lock by a separate act.

I also provide automatic means for preventing the throwing on of the latch dog 40 when the door is open, since it is obvious that should the door be open and should the latch be dogged against being pressed back, there would be danger of injury to the lock in the event the door should be 45 slammed, inasmuch as the latch would hit against the strike-plate and would not move back.

I thirdly provide an improved indicating 50 means in combination with the other elements, which is operated by the mere act of dead-locking the door to indicate that the room is occupied, a matter of great convenience when the invention is applied to

hotel bedroom doors which lead into the main corridor.

These and other advantages will be seen by the mechanic skilled in the art, from a reading of the following description and an examination of the accompanying drawings, in which—

Figure 1 is a plan view of the main frame of the lock assembled, the usual escutcheons, however, being absent. Fig. 2 is a view of the under side of the parts shown in Fig. 1. Fig. 3 is a view similar to Fig. 2, but inverted, some of the parts being broken away and other parts removed. Fig. 4 is a side elevation of the parts as shown in Fig. 3, looking from right to left. Figs. 5, 6 and 7 are detail views. Fig. 8 illustrates another detail in two positions. Fig. 9 is a front end elevation of the lock, with parts broken away. Fig. 10 is a section on approximately the line $\alpha-\alpha$ of Fig. 2, looking from right to left. Fig. 11 is a plan view showing certain parts. Figs. 12, 13 and 14 are detail views of roll-backs. Fig. 15 is a central longitudinal section through the axis of the knob spindles.

The present lock is of the so-called "unit" type, in which 1 constitutes a frame or backbone upon which all of the various lock parts, including the knobs, are mounted, so that the entire lock may be assembled at the factory and applied with the greatest ease to a door. As before stated, the usual escutcheons are omitted, as their construction and application are well understood in this type of lock.

2 represents the outside knob.

3 is a key which is insertible into the outer knob for the purpose of operating a roll-back spindle 4, which is connected with what I will term a key-controlled roll-back 5.

6 is a roll-back mounted upon the shank of the knob 2 and operable by the turning of the outer knob 2.

7 is a roll-back which is operable by an inner knob 8, said knob being connected to the roll-back 7 in any well known manner.

9 is a rotatable sleeve sometimes provided for the purpose of shifting the roll-back 6 longitudinally upon the shank of the knob 2. When this sleeve 9 is turned, it operates a plunger 10, which is operatively connected

through the roll-backs 5 and 7 with the roll-back 6, so that the latter can be moved either into the position shown in Fig. 1, in which it engages in a notch in the frame

1, whereby it cannot be turned, or may be moved to the left and close to the roll-back 5 so as to disengage it from the frame, thus enabling it to be turned, which latter position is indicated in dotted lines Fig. 15.

10 This means is a well known means for locking the outer knob against turning, and thereby making it impossible to gain access from the exterior without the use of a suitable key such as 3, by which key the roll-back 5 may be operated independently of

15 the knob 2. All of these roll-backs make an operative engagement with the bifurcated tail end 11 of a latch slide 12, which latter is connected to the latch 13, a spring 14 being provided to normally project the latch 13.

15 is a tilting frame which operates generally in the manner described in the aforesaid Letters Patent. This frame 15 is provided with a latch dogging arm 16, which is arranged to stand back of the latch 13 when the door is closed. The frame also has a cam arm 17, which is arranged to be engaged by an operating shoulder 18 on the tail piece 33 of a pivoted dog operator 19, which presents a bevel at the face of the lock corresponding in general appearance to a latch. When the door is closed, this operator 19 is pressed back by the strike-plate (not shown). When the door is open, it is projected. When the operator 19 is projected, the tilting frame 15 and its several arms stand as shown in Fig. 10.

20 When the operator 19 is pushed in, the shoulder 18 leaves the incline 17, so that the frame 15 may be tilted on its pivot through the action of a spring 20 to swing the arm 16 into position to act as a stop for the latch. A cam shoulder 21 on the

25 tail of the latch slide operates against an inclined tail end 22 of the frame, so that when the latch is retracted the very first movement of the latch slide will be to rock the frame 15 and move the dogging arm 16

30 away from the latch 13.

23 is a handle or thumb-turn carrying a spindle 24. This spindle 24 enters the hub of a dogging arm 25, which may be swung into the "off" position shown in Fig. 10, or may be turned down so that its front end will stand directly to the rear of the latch bolt, so as to squarely block or dead-lock the same. Obviously, by turning the thumb-turn 23 in either direction, this dogging de-

35 vice 25 may be operated, but it is important that means should be provided so that when the door is closed and dead-locked by this thumb-turn and dogging device 25, it would still be possible for the occupant of a room

40 to make his escape therefrom, in the event

of danger, by simply turning the inner knob 8. Accordingly I have provided a slide 27 suitably guided upon the frame 1 to move back and forth.

45 The hub of the dogging arm 25 is provided with an offset 28, which takes into a notch 27^a in the slide 27, whereby the movement of the slides to and fro will also operate the dog 25. The slide 27 is provided with a bifurcated rear end, which straddles the hub of the frame through which the knob spindles pass, and each end is also provided with a forward hooked extension 29-29, standing normally slightly ahead of the roll-back 7, which is operated by the inner knob. When the dog 25 is in the "off" position shown in Fig. 10, these hooked ends are spaced sufficiently from the roll-back 7 so that as the roll-back is moved it will not operate the slide 27. When, however, the dog 25 is turned into operative position, the hooks 29 will move back and rest close to the roll-back 7, so that the mere act of turning the inside knob 8 will cause one end or the other of the roll-back 7 to engage one of the hooked extensions 29, thereby pushing the slide 27 ahead and instantly releasing the dog 25, so that the continued movement of the roll-back 7 will retract the latch. It thus becomes apparent that, even though the thumb-turn has been turned to dead-lock the latch slide, absolutely preventing its retraction from the outside of the outer knob, the door can still be opened from the inside by merely turning the inner knob.

50 Obviously means should be provided to guard against the possibility of dead-locking the latch in its extended position by the thumb-turn when the door stands ajar, because if at such time the latch should be held extending, the door could not be closed, and if the door were slammed it would result in injury to the lock. To that end I provide an automatic locking means co-acting with the thumb-controlled latch dead-locking means which prevents the turning of the same from the unlocked to the dead-locked position. This means, in its preferred form, is also operated by the pivoted operator 19, and so long as the pivoted operator 19 is extended, as is the case when the door is ajar, it will hold out a locking detent pin 30, the said detent pin being guided in the frame 1, the forward end taking into a locking notch 31 in the slide 27. This locking position is plainly seen in Fig. 3, and, as shown therein, the rear end of the pin 30 will be seen to be supported upon a shoulder 32 on the tail piece 33 of the operator 19, when the latter is extended. When, however, the operator 19 is pushed back, as by the strike-plate, when the door is closed, this shoulder 32 moves away from the rear end of the pin 30, thus

freeing the same. When the pin is free, the slide 27 may be actuated. When, however, the pin 30 is held extended, as in Fig. 3, the slide 27 cannot be moved and consequently the thumb-turn 23 cannot be rotated to dead-lock the latch. 34 is a beveled incline at the rear end of the tail of the frame 27, which leads toward the locking notch 31, so that the detent pin 30 may be given slight movement under certain conditions, for example, so that the pin may be pushed out when the shoulder 32 does not stand behind the same.

35 is an indicator button, which is arranged to be carried in suitable socket guide 36 carried by the frame 1. This indicator button is designed to be located on the outer side of the door, and is so associated with the operating mechanism that when the door is dead-locked by the thumb-turn 23, said button 35 will stand in an indicating position whereby any one on the outside may know that the door has been locked from within. Such an indicator button as shown in former Patent No. 936,231, dated October 5th, 1909, may be successfully employed. In that case, as in the present case, the indicator button is arranged in line with the thumb-turn spindle 24 and may be shifted to the indicating and non-indicating position, and vice versa, by the mere turning of the spindle 24.

What I claim is:

1. In a lock, a spring latch bolt, a knob adapted to the inner side of a door to which the lock is applied, and means of connection between said knob and latch whereby the turning of the former will retract the latter, with a dogging device for said latch likewise operable from the inner side of the door, and means of connection between said dogging device and said knob whereby the turning of the knob will first cast off said dogging device and then retract the latch, with automatically operable means to pre-

vent moving the dogging device to the latch dogging position when a door to which the lock is applied stands ajar.

2. In a lock, a spring latch bolt, a knob adapted to the inner side of a door to which the lock is applied, and means of connection between said knob and latch whereby the turning of the former will retract the latter, with a dogging device for said latch likewise operable from the inner side of the door, and means of connection between said dogging device and said knob whereby the turning of the knob will first cast off said dogging device and then retract the latch, with automatically operable means to prevent moving the dogging device to the latch dogging position when a door to which the lock is applied stands ajar, and an automatic latch dogging device or stop arranged to prevent the reversion of the latch by pressure upon the exposed part thereof whenever a door to which the lock is applied is closed.

3. In a lock, a spring latch bolt, a knob adapted to the inner side of a door to which the lock is applied, and means of connection between said knob and latch whereby the turning of the former will retract the latter, with a dogging device for said latch likewise operable from the inner side of the door, and means of connection between said dogging device and said knob whereby the turning of the knob will first cast off said dogging device and then retract the latch, with automatically operable means to prevent moving the dogging device to the latch dogging position when a door to which the lock is applied stands ajar, and an externally located indicating device operable by the manually operable latch dogging device.

AUGUST ARENS.
